UNITED STATES PATENT OFFICE

118,905

DESIGN FOR A COMBINED RELISH BOWL
AND TRAY

Henry W. Lormor, Cleveland Heights, Ohio

Application October 21, 1939, Serial No. 87,785

Term of patent 3½ years

To all whom it may concern:

Be it known that I, Henry W. Lormor, a citizen of the United States and a resident of Cleveland Heights, in the county of Cuyahoga and State of Ohio, have invented a new, original, and ornamental Design for a Combined Relish Bowl and Tray, of which the following is a specification, reference being had to the accompanying drawings, forming a part thereof, in which

Fig. 1 is a top plan view of a combined relish bowl and tray showing my new design;

Fig. 2 is a side elevational view of same;

Fig. 3 is a vertical sectional view along the line 3—3 of Fig. 1, showing more clearly the contour and appearance of the design of the handles and tray of the article;

Fig. 4 is a vertical sectional view along the line 4—4 of Fig. 1, showing more clearly the design of the bowl part of the article; and

Fig. 5 is a sectional view along the line 5—5 of Fig. 1, showing further the appearance and design of the several elements of the article.

I claim:

The ornamental design for a combined relish bowl and tray, substantially as shown and described.

HENRY W. LORMOR.
